UNITED STATES PATENT OFFICE.

HUGH R. HAMILTON, OF WEBSTER, MASSACHUSETTS.

CUTTER-SHARPENING DEVICE.

1,244,493.

Specification of Letters Patent. Patented Oct. 30, 1917.

Application filed June 21, 1917. Serial No. 176,225.

To all whom it may concern:

Be it known that I, HUGH R. HAMILTON, a citizen of the United States, residing at Webster, in the county of Worcester and State of Massachusetts, have invented a new and useful Cutter-Sharpening Device, of which the following is a specification.

This invention relates to a cutter sharpening device designed for manual operation.

Many cutters and other small machine parts require frequent grinding and also require that the ground face be maintained at its original angle relatively to the other parts or faces of the article. It is extremely difficult to perform this grinding operation successfully while holding the article in the hand and pressing it against the face of a grinding wheel as is usually done. The correct face angle is commonly attained only after repeated trials and after grinding away a needless amount of valuable material, thereby correspondingly reducing the life of the cutter.

It is the general object of my invention to provide a sharpening device by which the cutter will be supported in a definite position and can be moved in a fixed path past an abrasive member, thus sharpening the cutter at the original angle with no loss of time or material.

With this general object in view, an important feature of my invention relates to the provision of a fixed abrasive member, preferably having at least one straight face, and to the further provision of means for yieldingly forcing the cutter against said member and for holding the cutter in definite angular relation thereto during the sharpening operation.

In the preferred form of my invention the abrasive member comprises an emery stone or other similar sharpening device having a rectangular cross section and firmly secured in a supporting stand. The cutter is yieldingly held in a carrier movable longitudinally of the stand and parallel to one of the straight faces of the grinding stone.

My invention further relates to arrangements and combinations of parts hereinafter described and more particularly pointed out in the appended claims.

A preferred form of my invention is shown in the drawings, in which—

Figure 1 is a plan view of my improved cutter sharpening device;

Fig. 2 is an end elevation thereof;

Fig. 3 is a sectional elevation taken along the line 3—3 in Fig. 1;

Fig. 4 is a side view of the cutter holder, and

Fig. 5 is a partial sectional elevation of the cutter taken along the line 5—5 in Fig. 2.

Referring to the drawings, my cutter sharpening device comprises a stand 10 having a shoulder 11 and flange 12 by which is positioned a sharpening stone or other abrasive member 13. The stone is securely held in longitudinal position by clamps 14 (Fig. 2) and clamping screws 15. The stone 13 is provided with a straight substantially vertical face 13^a which is engaged by the article to be ground.

The stand 10 is cut away to provide a guide-way 16 within which a carrier 17 is longitudinally slidable. The carrier 17 is grooved transversely at 18 and a holder 20 is mounted to slide transversely of the carrier in said groove. The holder 20 is provided with a recess 21 adapted to receive a spring 22, the outer end of which engages a plate 23 secured to the carrier 17 and closing one end of the groove 18. At its opposite end the holder 20 is cut away to form a seat 24 for the cutter C which is shown in the drawings as secured by a screw 25. A handle or knob 26 is mounted on the upper side of the holder 20.

The operation of the device is extremely simple. The holder is preferably removed from the carrier while the cutter is secured thereto, the face to be ground being set at a right angle to the sides of the holder. The holder is then placed in the carrier, the spring 22 being compressed by pressure upon the handle 26 until the cutter slips freely past the stone 13. When the holder is in position in the carrier the spring is released and forces the cutter yieldingly against the face 13^a of the grinding stone. The carrier 17 is then moved back and forth along the guide-ways 16 in the stand 10 until the face of the cutter C has been ground to the required extent.

During this operation the spring 22 keeps the cutter pressed against the grinding stone with the desired pressure and the cutter is held at a fixed angle to the stone during the entire grinding operation. If the cutter has been accurately placed upon the holder 20 it will be ground with a slight amount of labor and no waste of material.

While I have shown only one form of cut-

ter in the drawings it will be understood that the device is capable of use with a wide variety of cutters and other small articles.

5 Having thus described my invention, it will also be evident that changes and modifications can be made therein by those skilled in the art without departing from the spirit and scope of my invention as set forth in the 10 claims, and I do not wish to be otherwise limited to the details herein disclosed, but what I claim is:—

1. A cutter sharpening device having, in combination, an abrasive member having a straight face, a stand to which said member is secured, means to support a cutter on said stand at a fixed angle to the face of said member, said means including devices forcing said cutter toward said member but permitting yielding movement of said cutter away from said member without change of angle, and means to guide said cutter along said straight face at said fixed angle thereto.
2. A cutter sharpening device having, in

Copies of this patent may be obtained for five cents each, by addressing the "Commissioner of Patents, Washington, D.C."

combination, a stand, an abrasive member, 25 means to secure said member in fixed position in said stand, a carrier slidable longitudinally of said member in said stand, a holder slidable transversely of said member in said carrier, means to secure a cutter to 30 said holder, and means to press said holder and cutter yieldingly toward said abrasive member.

3. A cutter sharpening device having, in combination, a stand with a guide-way 35 therein, an abrasive member having a straight side extending parallel to said guide-way, means to secure said member in said stand, a carriage slidable in said guide way, a holder slidable in said carriage toward and from said abrasive member, a spring to force said holder toward said member, and means to secure a cutter to said holder.

In testimony whereof I have hereunto 45 affixed my signature.

HUGH R. HAMILTON.
